UNITED STATES PATENT OFFICE.

GLENN A. SHAFFER AND FRANKLIN H. WIRTZ, OF GREEN BAY, WISCONSIN.

PAPER-FOLDING MACHINE.

Application filed June 19, 1922. Serial No. 569,489.

To all whom it may concern:

Be it known that we, GLENN A. SHAFFER, a subject of the King of England, and FRANKLIN H. WIRTZ, a citizen of the United States, residing at Green Bay, in the county of Brown and State of Wisconsin, have invented certain new and useful Improvements in Paper-Folding Machines, of which the following is a specification.

10 The invention relates to a machine for folding paper napkins, and more particularly to the class of machines for folding paper used in hotels and restaurants for table use.

15 The primary object of the invention is the provision of a machine of this character, wherein strips of paper are fed into the same and automatically folded and cut to form paper napkins, the latter being delivered into containers or receivers in a novel manner.

Another object of the invention is the provision of a machine of this character, wherein the folding and cutting operations 25 thereof are novel, so that said machine performs in an efficient manner.

A further object of the invention is the provision of a machine of this character, wherein the folded napkins are packed in 30 the receiver or container through the medium of novel mechanism, which operates simultaneously with the other parts of the machine.

A still further object of the invention is 35 the provision of a machine of this character, which is comparatively simple in construction, thoroughly reliable and efficient in operation, strong, durable, automatic in performance and inexpensive to manufacture 40 and install.

Other objects will be in part obvious and in part hereinafter pointed out.

The improvements in details and arrangements of the parts will be apparent from an 45 inspection of the accompanying drawings, in connection with the specific description hereinafter contained, and wherein the preferred embodiment of the invention is disclosed for the purpose of imparting a full 50 understanding of the same.

In the accompanying drawings:

Figure 1, is a front elevation of the machine constructed in accordance with the invention.

55 Figure 2, is a side elevation thereof.

Figure 3, is an enlarged sectional eleva-

tion taken transversely through folding and cutting rolls in their assembled relation to each other.

Figure 4, is a view taken on the line 4—4 of Figure 3.

Figure 5, is a detail elevation showing the plungers and operating mechanism therefor to deliver the folded napkins into the receiver or container.

Figure 6, is a sectional view on the line 6—6 of Figure 5.

Figure 7, is a fragmentary horizontal sectional view through the receiver or container.

Figure 8, shows one of the positions of the folding and cutting mechanism and the strip of paper.

Figure 9, shows another position of the folding and cutting mechanism and the strip of paper.

Figure 10, shows a further position of the folding and cutting mechanism and the strip of paper.

Similar reference characters indicate corresponding parts throughout the several views in the drawings.

Referring to the drawings in detail, A, designates generally a main frame structure of the desired type for the machine, having spaced apart side sections 10, which are connected at their upper ends by transverse tie rods 11, while bolted or otherwise fastened to said side sections at their lower portions is a vacuum box or tank 12, the same being located between the side sections of the main frame.

Secured to the rear edges of the side sections 10, of the frame A, are the uprights 13, of a stand B, for removably supporting paper rolls 14 and 15, the same being superposed relative to each other, and each is carried upon a cross arbor 16, mounted in releasable bearings.

On each arbor 16, is a brake drum 18, about which engages a releasable and adjustable brake band 19, the latter being adjustable by the adjusting device 20, so that the band 19, can be tightened or slackened about said drum, as the occasion may require. The 100 uprights 13, are joined through the medium of a cross rod 21, to prevent spreading thereof and to add rigidity to the stand B.

Journalized in the side sections 10, of the main frame A, in the top beams 23, thereof are transversely arranged front and rear guide rollers 24 and 25, respectively, over

which are trained the paper strips 26 and 27, of the paper rolls 14 and 15, respectively, while suitably journaled in the uprights 13, is a driving shaft 28, carrying a belt wheel 29, for connection with any suitable power plant, the shaft 28, also being fitted with a sprocket wheel 30, over which is trained an endless sprocket chain 31, the same being also trained over a sprocket wheel 32, fast 50 upon the journal of the front guide roll 24, so that motion will be transmitted thereto. A sprocket chain 33, is trained over sprocket wheels 34 and 35, on the journals of the respective guide rollers 24 and 25, so that the 55 same will rotate in unison.

Suspended from the upper tie rods 11, are forwardly inclined folders 36, over which pass the strips 26 and 27, for the primary folding of the same, after being unwound 20 from the rolls 14 and 15, respectively, these folders are supported by braces 37, suitably mounted in the main frame A, as shown in Figure 2, of the drawings.

In the side sections 10, of the main frame 25 A, below the folders are opposed face plates or cheeks 38, the same being fastened in place in any suitable manner and in these plates are journaled the roll folding and cutting mechanism, comprising upper presser and feed rolls 39 and 40, respectively, the 30 presser roll 39, being carried upon a shaft 4, loosely journaled in said plates 38, and acted upon at each end by spring tensioned bearings 42, working in boxings or housings 43, formed on the respective plates 38, said springs being adjustable in the boxings or 35 housings.

The feed roll 40, has formed therein longitudinally of the same a groove 47, in which 40 is adjustably held an angle knife 48.

The angle knife 48, cooperates with a saw blade knife 49, mounted in a suction or partially vacuum roll 50, which is located forwardly and slightly below the feed roll 40, 45 and this roll 50, is journaled in gland 51 and bearing 52, respectively, formed on the plates 38, while the journal 44, of the feed roller 40, has mounted thereon at its inner end a beveled gear 45, meshing with a companion bevel gear 46, mounted on shaft 28, so that motion will be imparted from one 50 gear to the other.

The roll 50, is of hollow formation to form 55 a suction chamber 22, therein and in its peripheral portion adjacent to the knife 49, are rows of perforations 53, while the outer surface of said roll at this locality is provided with serrations 54, whereby the paper can be held more firmly on the roll, when 60 taken from the roll 40, under the action of the suction through the perforations 53, so that said paper will be trained about the roll 50.

Below the rolls 40 and 50, are take-off and 65 folding rolls 54 and 55, respectively, the roll

54, being journaled in the plates or cheeks 38 while the roll 55, is journaled in an identical manner as the presser roll 39, hereinbefore described. The take-off roll 54, is fitted with a spring tensioned wiper member 56, while the roll 55, is formed with a clearance channel 57, for the knife 49, during the rotation of the rolls, in the folding and cutting operation of the mechanism. 70

Located beneath the rolls 54 and 55, are 75 strippers 60, and 61, respectively, which are hung upon cross rods 62, and 63, as is clearly shown in Figures 3 and 5, of the drawings. These strippers 60 and 61, have their upper stripper ends adjacent to the rolls 54 and 55, 80 to strip the folded napkins therefrom, said strippers being spaced apart to provide a way 65, for the passing of the napkins downwardly therethrough, while the strippers 60, at their lower ends are formed with hook 85 like stops 66, to bring the napkins to rest at this point, for a purpose presently described.

Coupled at 67, with the packing gland 51, is a suction pipe 68, which leads downwardly exteriorly of the main frame A, and is connected as at 69, with the vacuum box or tank 12, the latter being in communication at its bottom at 70, with a suction tube 71, leading from a suction fan (not shown), so that suction will be maintained in the box or tank 90 95 12, during the operation of said fan.

Rising from the box or tank 12, is a vertical suction housing 72, for the entrance ends of containers or receivers 73, in the form of troughs for the folded napkins 100 delivered from the machine in a manner presently described.

The troughs formed by the receivers or containers are detachably secured to the housing 72, as at 74, and are preferably 105 made from sheet metal, the inner or entrance end of each trough being formed with perforations 75, communicating with the suction chambers 76, in the housing 72, for effecting a suction action upon the napkins when initially admitted to the container or receiver. 110

On the inner face of the housing and extending slightly over the entrance ends of the troughs 73, are retainer members 77 115 which prevent the retrograde movement of napkins delivered into the containers or receivers.

Formed on the vertical portion of the housing 72, beneath the entrance ends of the troughs are pivots 78, for the hinge connection of rocker arms 79, carrying plungers 80, working through the entrance ends of the troughs 73, to push the napkins thereinto, these plungers being movable between 120 the stripper plates 60 and 61, to remove the folded napkins from the ways 65, and to advance them into the containers or receivers. 125

Each rocker arm 79, is fitted with a bear- 130

ing roller 81, adapted to work on a cam 82, fast upon a rotating shaft 83, journaled in brackets 84, on the box or tank 12, the shaft being fitted at one end with a sprocket 5 wheel 85, over which is trained a sprocket chain 86, the same also being trained over a sprocket wheel 87, mounted on a counter shaft 88, journaled in the plates or cheeks 38, and this shaft is fitted with a delivery roll 89, coacting with a presser roll 90, opposed thereto, for the advancing of the folded napkins in the ways 65, until brought to rest upon the stops 66, on the strippers to position the napkins at the 10 mouth or entrance to the trough.

Suitable gears are on the rolls 54, and 89, and mesh with gear 91, so that these rolls will cooperate as a power train of gearing to transmit motion through the 20 chain 86, to the cam shaft 83, for operating the plungers 80, at the desired intervals of time, the roll 54, being incut at 92, for a portion of its periphery to alternately take off the napkins from the roll 50, and free 25 said napkins subsequently to the final folding thereof, and advanced into the ways 65, of the strippers to be taken up by the delivery roll 89, and thereafter advanced by the plungers 80, into the containers or receivers. 30

When the plungers 80, advance the folded napkins into the entrance ends of the troughs the edges of the napkins entering ride over the retainer members 77, as the napkins are 35 springy, and are pushed into the troughs about one-half inch, whereupon the inrushing air into the perforations 75, snaps the sides of the napkins flat against the body or group of napkins already within the 40 troughs, and as the plungers retrieve or are withdrawn the mass of napkins in the troughs move against the retainer members 77, and thus are held therein.

The suction accelerates the operation at 45 the just mentioned point of the machine, since the springy characteristic of the paper would cause the napkins to flatten out without the suction, but at a slow ratio of time.

It will be apparent that the strips of paper 50 from the rolls 14 and 15, are first folded by the folders 36, and thereafter are acted upon by the suction roll 50, coacting with roll 40, the once folded paper being trained about the roll 50, until whipped therefrom 55 at the proper interval by the roll 54, which with the roll 55, folds the paper again, as the latter is cut off of the strip by the knives 48 and 49, the required size, and thence the twice folded paper napkins are 60 advanced into the ways in the strippers 60 and 61, and thereafter pushed into the containers or receivers 73, for the massing of the folded paper napkins therein.

The suction in the roll 50, causes the 65 papers to stick thereto until pulled off by

the wipers 56, in the rolls 54, for the second and final folding of the napkins.

In Figure 3, of the drawings there is shown to the right of the roll 40, a printing platen 93, which receives ink from inking 70 rolls 94 and 95, these being supplied with printing ink from any suitable source of supply, and in the use of the printing device any desirable printing may be effected on the product. 75

What is claimed is:

1. A machine of the character described, comprising a main frame having a vacuum box in its lower portion, means for supporting and guiding paper to the frame, a forwardly inclined folder in the frame for the primary folding of the paper, coacting presser and feed rolls below the folder, the feed roll being formed with a longitudinal groove, an angle knife in said groove a 85 vacuum roll adjacent to the feed roll in communication with the vacuum box and having perforations in a portion thereof, a saw blade knife next to the perforations in the vacuum roll, coacting take-off and folding rolls below the vacuum roll, a wiper member carried by the take-off roll, strippers beneath the last named rolls, and mechanism for transferring the folded sheets from the strippers to a receiver. 90 95

2. A machine of the character described, comprising a main frame having a vacuum box in its lower portion, a stand connected with the frame for supporting a paper roll, 100 guide means in the upper portion of the frame, for the paper from the roll, a forwardly inclined folder in the frame for the primary folding of the strip trained over the guide means from the paper roll, coacting presser and feed rolls below the folder, the feed roll being formed with a longitudinal groove, an angle knife in said groove, a vacuum roll adjacent to the feed roll and having perforations in a portion thereof, a saw blade knife next to the 110 perforations in the vacuum roll, coacting take-off and folding rolls below the vacuum roll, a wiper member carried by the take-off roll, strippers beneath the last named rolls, mechanism for transferring the folded sheets from the strippers to a receiver, and means for creating a vacuum in the vacuum roll and connected with the vacuum box. 115

3. A machine of the character described, comprising a main frame, a folder in the upper portion of the frame for initially folding product of paper, roll mechanism beneath said folder for again folding and cutting the product into predetermined size, strippers coacting with said mechanism and having a way for the severed and folded product, a receiver for the folded product, and mechanism for taking the severed folded product from the way and delivering same 120 successively into the receiver. 125 130

4. A machine of the character described, comprising a folder for initially folding a product of paper, roll mechanism beneath said folding for again folding and cutting the product into predetermined size, strippers coacting with said mechanism and having a way for the severed and folded product, a receiver for the folded product, mechanism for taking the severed and folded product from the way and delivering same successively into the receiver, and mechanism for directing a product of paper to the folder. 40
5. A machine of the character described, comprising a main frame, a folder in the upper portion thereof for initially folding strips of paper, roll mechanism beneath said folder for again folding and cutting the strips into predetermined size, strippers coacting with said mechanism and having a way for the severed and folded strips, a receiver for the folded strips, mechanism for taking the severed folded strips from the way and delivering same successively into the receiver; mechanism for directing a strip of paper to the folder, and means for effecting a suction in one of the rolls of the roll mechanism. 50
6. A machine of the character described, comprising a main frame, a folder in the upper portion thereof, for initially folding strips of paper, roll mechanism beneath said folder for again folding and cutting the strips into predetermined size, strippers coacting with said mechanism and having a way for the severed folded strips, a receiver for the folded strips, mechanism for taking the severed folded strips from the way and delivering same into the receiver, mechanism for directing a strip of paper to the folder, means for effecting a suction in one of the rolls of said roll mechanism, retainers in the receiver at the entrance end thereof to prevent retrograde movement of the folded strips when delivered thereto. 55
7. A machine of the character described, comprising a main frame, a folder in the upper portion thereof for initially folding strips of paper, roll mechanism beneath said folder for again folding and cutting the strips into predetermined size, strippers coacting with said mechanism and having a way for the severed folded strips, a receiver for the folded strips, mechanism for taking the severed folded strips from the way and delivering same into the receiver, mechanism for directing a strip of paper to the folder, means for effecting a suction in one of the rolls of said roll mechanism, retainers in the receiver at the entrance end thereof to prevent retrograde movement of the folded strips when delivered thereto, and means for creating an inrush of air in the entrance end of the receiver to mass the folded strips delivered therein together. 60
- In testimony whereof we affix our signatures.
- GLENN A. SHAFFER.
FRANKLIN H. WIRTZ.
